PROCESS FOR ENHANCING THE OCTANE NUMBER OF CATALYTICALLY CRACKED NAPHTHA FRACTIONS

Weldon G. Annable, Mundelein, and William L. Jacobs, Crystal Lake, Ill., assignors to The Pure Oil Company, Chicago, Ill., a corporation of Ohio

Application November 5, 1956, Serial No. 620,416

5 Claims. (Cl. 208—76)

This invention relates to the production of high octane number gasolines. It is more specifically concerned with improving the sensitivity of a gasoline produced in a catalytic cracking process.

In order to afford a more realistic expression of the road performance characteristics of gasoline-type motor fuels, a "sensitivity" factor is employed as a criterion. Sensitivity is defined as the difference between the F-1 or research octane number (CRC designation F-1-545) and the F-2 or motor octane number (CRC designation F-2-545), as conventionally obtained. Because refining techniques generally used in the processing of crude petroleum oil fractions are limited in their ability to produce gasolines of high F-2 antiknock quality, the sensitivity of gasolines produced in this manner has increased appreciably since the advent of these processes. An important reason for the liability of the more sensitive fuels is the increased use of automatic, automotive transmissions which raise the speed of maximum octane requirement. The trend toward motor fuels of increased sensitivity is due primarily to the significant position of catalytic cracking processes in the refiner's scheme of operations.

The formula for finished high-octane-number gasolines includes as the major constituent a full-boiling-range gasoline produced in a conventional catalytic cracking process such as F.C.C., T.C.C., Houdry process or the like. Blended with this base fuel are a number of other blending components such as gasoline fractions produced by reforming, polymerization, alkylation, isomerization, etc., of specially selected fractions. It is therefore essential that the fuel component constituting the major portion evince maximum performance characteristics. Accordingly, the primary object of this invention is to upgrade the octane number characteristics of a gasoline obtained from a catalytic cracking process. It is another object of this invention to decrease the sensitivity of a gasoline produced in a catalytic cracking process. A further object of this invention is to employ an integrated, split treatment of a gasoline manufactured in a fluid catalytic cracking process to produce a high-octane gasoline. These and other objects will be made apparent from the following detailed description of this invention.

In the figure is shown schematically a processing flow diagram of the refining process of this invention.

The key refining process in the production of high octane gasolines is catalytic cracking wherein gas-oil streams from atmospheric distillation, vacuum distillation, and bottoms-processing units are treated to give a high yield of a high-grade gasoline. Catalytic cracking processes which are comprehensively described in the prior art are categorized as three different types, viz., fixed bed, e.g., Houdry; moving bed, e.g., T.C.C.; and fluid systems, e.g., F.C.C. For given conditions of operation and catalyst compositions, the chemistry of these processes can be considered essentially the same, involving C-C scission, aromatization, isomerization, and polymerization. For this reason, as pointed out in *Progress in Petroleum, Advances in Chemistry Series #5, A.C.S., 1951* at page 12, "the gasolines produced in the catalytic cracking of a wide variety of petroleum feed stocks have notable similarities

2

in composition, physical properties, and engine performance."

According to this invention, it has been found that the octane number characteristics of a gasoline of this nature can be improved by fractionating the gasoline to obtain a low-boiling fraction and a high-boiling fraction. The low-boiling fraction is mildly hydrogenated and the high-boiling fraction is reformed in the presence of a noble metal catalyst. By blending the treated fractions a full-boiling-range gasoline having a high octane level and a low sensitivity is prepared. In the figure is shown a processing scheme for carrying out this invention. A gas-oil feed stock, obtained from a suitable source not shown, is introduced through line 10 into a conventional catalytic cracking process 11. The reaction effluent from the cracking process is transferred through line 12 to fractionator 13 where it is separated into an unstabilized gasoline cut, and other fractions boiling above the gasoline range. The gasoline cut is passed via line 14 to second fractionator 15 where it is stabilized and fractionated into a low-boiling fraction and a high-boiling fraction. The lower-boiling fraction is withdrawn from fractionator 15 through line 16 and processed in hydrogenation unit 17. The higher-boiling fraction leaves fractionator 15 and is sent to reforming unit 18 through line 19. The reaction effluent leaving hydrogenation unit 17 is condensed and the liquid product transferred through line 20. Similarly the liquid reformate from reforming unit 18 passes through line 21 to a point of confluence with line 20. The respective streams are blended in line 22 to produce a gasoline product having a high F-1 octane number and a low sensitivity.

In the treatment of a variety of gasolines obtained in the catalytic cracking of suitable petroleum fractions the basic split treatment technique outlined above can be effectively employed. For practical reasons, however, it is preferred that the high-boiling fraction be hydrofining prior to reforming by means of a conventional guard case operation (World Petroleum 26 (2), 44-6). By pre-treating this fraction in this manner, better temperature control during reforming is obtained because the hydrogenation reaction, which is generally a concomitant reaction during the reforming, is exothermic. Furthermore, reforming catalysts employed in this invention are sensitive to sulfur. Therefore by pre-hydrofining the high-boiling fraction, the sulfur content of this fraction is substantially reduced and catalyst poisoning mitigated. In commercial reforming operations, pre-hydrofining of the feed stock is effected by having a guard case ahead of the reformer in the process scheme. The pre-hydrofining of this fraction, if employed, is carried out under the same conditions which are employed in mildly hydrogenating the low-boiling fraction. Accordingly an alternative processing scheme would involve the hydrogen treating of the full-boiling-range gasoline obtained from a catalytic cracking process followed by the above-described, basic, split-treatment technique.

To further illustrate the invention, a gasoline was produced in the fluid catalytic cracking of a Mid-Continent gas-oil having the following characteristics:

60	API gravity	27.2
	Boiling range	
65	IBP	448
	10%	555
	50%	733
	70%	812
	E. P.	1000
70	Sulfur, wt. percent	0.55
	Carbon residue; percent wt.	0.30
	Aniline point, ° F.	184
	Vis., SUS, 100° F.	120
	Pour point, ° F.	+80

The cracking was carried out on a commercial scale, in the presence of a conventional silica-alumina cracking catalyst, employing the following operating conditions:

Reaction temperature ° F. 905
Reaction pressure p.s.i.g. 16
Space velocity, v./hr./v. 4
Conversion percent 55

The stabilized gasoline produced was fractionated into consecutive fractions consisting of a low-boiling fraction and a high-boiling fraction, having the characteristics tabularly summarized in Table I:

The low-boiling fraction was hydrogenated in a 1" stainless steel reactor in which the top section contained the preheater. The reactor fits in a bronze block maintained at the operating temperature. The hydrogenation was carried out under mild operating conditions employing 9% molybdenum oxide on alumina as the hydrogenation catalyst (Filtrol R-3241). This operation is summarized in Table II.

It is evident that the foregoing illustrative example is non-limiting and that other manipulative techniques can be employed in carrying out this invention. In selecting the cut-point for separating the low-boiling fraction and high-boiling fraction, the proportion of the full-boiling-range gasoline which is to be hydrogenated is determined experimentally. The selected low-boiling fraction will be characterized by being that fraction which upon being mildly hydrogenated and blended with the remaining fraction, provides a full-boiling-range gasoline having a maximum appreciation in motor octane number (F-2) with a minimum depreciation in research octane number (F-1). Generally, the low-boiling fraction will have an ASTM end-point of about 175° F.; however, this may vary from about 150° to 250° F. The importance of empirically ascertaining the cut-point is illustrated by fractionating a full-boiling-range gasoline, obtained from the fluid catalytic cracking of a gas-oil, to provide the three low-boiling fractions, (1) I.B.P.—150, (2) I.B.P.—175, (3) I.B.P.—200, described in Table VI. These respective fractions were processed employing, as a hydrogenation catalyst, a composite comprising a silica-alumina support having incorporated therein 5% nickel, but molybdena on alumina or any other hydrogenation catalyst may be used. The effect of boiling range on reducing the sensitivity of the blends containing the various hydrogenated fractions is shown in Tables VII and VIII. These tables show respectively the operating conditions and results obtained, and a comparison of the effect of hydrogenating the various fractions on the full-boiling-range gasoline after blending back each fraction. In the event that maximum octane number improvement

is not desired, the process can be carried out without reforming the higher-boiling fraction, and thus provide principally an enhancement in the sensitivity of the gasoline.

¹ Liquid volume hourly space velocity.

The catalyst employed in these hydrogenation steps is one commonly used in a hydrogenation reaction involving hydrocarbon feed stocks. Preferably oxides and salts of, or elemental, group VI or VIII metals, either alone or supported on a suitable carrier such as silica-alumina, alumina, kieselguhr, etc., are used, including but not limited to nickel, platinum, copper chromite, sulfides and oxides of nickel, molybdena, cobalt, tungsten and others. A preferred catalyst for this purpose is a molybdena-on-alumina catalyst described in our copending application Serial Number 593,821, filed June 26, 1956.

In a similar manner, the catalytic reforming of the higher-boiling fraction employs customary processes utilizing group VIII noble metal catalysts comprising platinum or palladium deposited on a suitable siliceous carrier. A number of compositions of this nature are described in the patent art. For example, see U.S. Patents 2,479,109; 2,478,916; 2,550,531; 2,589,189; 2,750,329 and others. It is preferred in carrying out the reforming phase of this invention to employ a platinum catalyst containing 0.2 to 0.6% platinum on a high-area alumina having a surface in excess of 350 square meters per gram. The catalyst may be in the extruded form having diameters of $\frac{1}{2}$ ".

The reforming operation carried out in accordance with this invention is conducted at temperatures in the range of 900° to 1050° F., and pressures of about 300 to 600 p.s.i.g. A liquid volume hourly space velocity

of 1 to 3 can be used with a molar ratio of hydrogen/hydrocarbon feed of 1 to 6:1.

The catalytic gasoline to be upgraded may be produced by any known method using static bed reactors, moving bed reactors or fluidized bed reactors. The charge stock should contain at least 50% virgin material but may contain a minor amount of recycle or extraneous material. The boiling range of the charge should run from about 450° F. up to 1000° F. or more. The catalyst employed may be either a natural or synthetic cracking catalyst and may be in powdered, granular, or specially manufactured forms. Conventional catalytic cracking conditions employing temperatures of about 900° to 1000° F. and conditions to provide 50 to 60% conversions are used.

From the foregoing data, it is seen that by means of the integrated hydrogenation-reforming process of this invention a gasoline from a catalytic cracking process can be upgraded to produce a high octane number product with decreased sensitivity. If the full-boiling-range gasoline is hydrogenated, there is a loss in both the motor octane number (F-2) and research octane number (F-1). It has been found that while gasolines from catalytic cracking processes are receptive to treatment in accordance with this invention, gasolines obtained from thermal cracking do not similarly respond. For example, in mildly hydrogenating a low-boiling gasoline fraction having an ASTM boiling range of I.B.P.—175° F., produced by the thermal cracking of a gas-oil feed stock, there was experienced a decrease in sensitivity; however, there was a depreciation in both the motor octane number (F-2) and the research octane number (F-1). Therefore, this invention is limited in accordance with the process details set forth in the appended claims. It is evident, however, that various modifications of the described process can be made by those skilled in the art without departing from the scope of this invention.

We claim:

1. A process for enhancing the octane number and improving the sensitivity of full-boiling range leaded gasoline produced in the catalytic cracking of petroleum gas oil comprising separating from said gasoline a plu-

rality of consecutive higher- and lower-boiling fraction pairs, said lower-boiling fractions having end-boiling points differing substantially from each other and ranging from about 150° to 250° F., catalytically hydrogenating each of said lower-boiling fractions by contacting with hydrogen in the presence of a hydrogenation catalyst selected from the group consisting of nickel on silica-alumina support and molybdena on alumina support, at a temperature in the range of about 550° to 700° F., a pressure in the range of about 350 to 500 p.s.i., a liquid volume hourly space velocity in the range of 1-5, and a hydrogen rate in the range of 1000-3000 cubic feet per barrel, blending each hydrogenated fraction back with the higher boiling fraction from which it was separated and with the desired amount of tetraethyl lead, determining the sensitivity of the resulting blend in each case and thereafter catalytically hydrogenating under the aforesaid hydrogenating conditions that fraction of the gasoline corresponding to the sample which gave the lowest sensitivity without substantial decrease in research octane number of the blend, catalytically hydroforming the higher boiling fraction of the gasoline and blending the resulting hydrogenated fraction with the higher boiling hydroformed fraction to obtain a full boiling range gasoline of high octane number and low sensitivity.

2. Method in accordance with claim 1 in which

hydrogenation is carried out at a temperature of about 550-600° F., pressure of about 500 lb./sq. inch, liquid hourly space velocity of about 1.0-2.2 and hydrogen rate of about 1500-3000 cubic feet per barrel of gasoline fraction charged.

3. Process in accordance with claim 1 in which the fraction subjected to mild hydrogenation has an ASTM end point of about 175° F.

4. A process in accordance with claim 2 in which 10 hydrogenation is carried out in the presence of a catalyst comprising a major portion of alumina and a minor amount of molybdena.

5. A process in accordance with claim 4 in which 15 said higher-boiling fraction is hydroformed at a temperature of 900-1050° F., a pressure of 300-600 p.s.i.g., a liquid volume hourly space velocity of 1-3, and a molar ratio of hydrogen to hydrocarbon feed of 6-1:1.
